MOTORIZED ORNITHOPTER

Percival H. Spencer, 420 Palisades Ave.,
Santa Monica, Calif.

Filed July 10, 1961, Ser. No. 65,862

Term of patent 14 years

(Cl. D34—15)

FIG. 1.

FIG. 2.

FIG. 3.

FIG. 4.

FIG. 5.

FIG. 1 is a perspective view of a motorized ornithopter showing my new design;

FIG. 2 is a side view;

FIG. 3 is a front view;

FIG. 4 is a bottom view of the body portion of my design with portions of the wings and tail removed for convenience of illustration; and

FIG. 5 is a top plan view showing my new design.

I claim:

The ornamental design for a "motorized ornithopter," as shown and described.
